Primary Examiner — George D. Kirschbaum*Assistant Examiner* — Kathleen L Jones(74) Attorney, Agent, or Firm — Oblon, McClelland, Maier & Neustadt, L.L.P.(57) CLAIM

The ornamental design for a display screen with a graphical user interface, as shown and described.

DESCRIPTION

1. Display screen with a graphical user interface

1.0 : Front

The outermost, evenly-spaced broken lines show a display screen; the dash-dot broken line represents the boundary of the claimed design; all other evenly-spaced broken lines show portions of the graphical user interface; all broken lines form no part of the claimed design.

1 Claim, 1 Drawing Sheet
